4 Claims. (Cl. 234—4)

Description of the Drawing

The single FIGURE of the drawing is a circuit diagram showing parts of an auxiliary apparatus for operating the keyboard of a tape-perforating machine, as provided by the invention, and also showing parts of a tape perforating machine.

Specification

This invention relates broadly to the operation of keyboards of machines which are used in the art of typesetting, typesetting and the transmission of messages and, more particularly, to machines which perforate tape which is used in the operation of typesetting or typesetting machines or the sending of messages, typewriting machines, electrotypers, Photon machines, machines for the automatic electrical control of typesetting or typesetting machines, Varitype machines, machines for typing matter from which any printing plates are made, and the like. While the invention is useful in the operation of the keyboards of such machines, it will be particularly described in this application in connection with, and as applied to, auxiliary apparatus for operating a machine which perforates tape which is used to operate and control a typesetting or typesetting machine such as the Linotype, Intertype and Monotype machines.

It has, for many years, been the general practice in the printing art to cast and set type by the use of machines such as the Linotype. Such machines are equipped with a special keyboard usually having ninety keys, although sometimes a greater and sometimes a smaller number of keys are provided, and the operation of such machines must be performed by highly skilled personnel who are able to operate the special keyboard and perform other duties essential to the most efficient operation of these very complex machines.

It has heretofore been proposed to operate such typesetting machines by means of a perforated tape prepared on a machine having a keyboard which corresponds to the standard typewriter keyboard with the addition of certain keys for performing operations and producing characters which are necessary in printing but not in typewriting. Such machines are now available commercially, a typical one being known as the Teletypesetter. It has been found, however, that the over-all efficiency and cost of typesetting with the use of such auxiliary tape perforating machines are less favorable than the efficiency and cost of operation with the use of skilled Linotype operators who are particularly skilled in the operation of typesetting machines having the standard Linotype keyboard. The use of machines for perforating tape for the operation of typesetting machines has become widespread, however, and it will be apparent that further and very important advantages would be produced in the over-all efficiency and costs of a printing plant by the operation of such machines by skilled operators having knowledge of the entire typesetting, typesetting and printing operations and, particularly, being skilled in the use of the standard Linotype keyboard.

In my United States Letters Patent Nos. 2,679,902, 2,737,240 and 2,737,616, and in United States Letters Patent to Happel, Arvin and Murphy, No. 2,739,649,

2

there is disclosed apparatus, including a keyboard having keys positioned and arranged substantially as in a standard Linotype machine keyboard, for association with a tape perforating machine such as the Teletypesetter, which apparatus, upon operation of its keys, will actuate the keys of the tape perforating machine to perforate tape in the normal manner of operation of the tape perforating machine. The apparatus provided by these patented inventions will be referred to hereafter in this specification as 5 the "auxiliary keyboard apparatus," and the tape perforating machine will sometimes be referred to as the "TTS."

The present invention has to do with this auxiliary keyboard apparatus and, while it will be described in this 15 specification in connection with a specific problem, namely, the setting of type for telephone directory listings of name, address and number, it is to be understood, and is and will be so understood by those skilled in the art, that it is of general utility and application in the typesetting 20 and composing fields.

In the setting of type for printing modern telephone 25 directories a major increase in cost and expenditure of time is caused by the necessity to transpose the letters of the conventional telephone number into numerals. Thus, the conventional telephone number AD 2-2543 must be transposed to the modern number 232-2543 because, on the conventional telephone dial, the letters A and D correspond, respectively, to the numbers 2 and 3. On the conventional dial the letter groupings, with 30 their corresponding numbers, are the following:

ABC	2	MNO	6
DEF	3	PRS	7
GHI	4	TUV	8
JKL	5	WXY	9

In setting type or punching tape to set type for printing telephone directories having the all-number listing it has been necessary for the operator to transpose the letters of the conventional listing to the corresponding numbers in accordance with the foregoing table. This transposition must be done either mentally or by visual reference to a table and, in either case, has caused loss of time and added cost. It has therefore been a principal object of this invention to provide means for effecting this transposition upon depression of each letter key of the auxiliary apparatus, which is one of the letters of the conventional telephone number, so that the operator is relieved entirely of the necessity of making the letter to number transposition.

It will be observed that all telephone numbers, as now universally used, have a group of three units, which may be two letters and one number or three numbers, and a group of four units, which are always all numbers, the two groups being separated by a hyphen, as illustrated by the number 232-2543, which is referred to above. Thus, in setting the type for a telephone directory listing of all-number numbers, the column of numbers, e.g., 232-2543, is justified at both the left and right sides. However, because of differences in the widths of the name and address part of the listings, the distance between the end of such part and the first number of the all-number listing varies from line to line. This has required the operator to compute for each line the number of leaders required between the name and address part and the number part of each listing, with consequent loss of time and added cost, and it has been another principal object of the invention to provide means for stopping the leader operation at the proper place to begin the operation of perforating the tape with the perforations characteristic of the telephone number or, if type is being set directly, to begin the setting of the telephone number.

With this means for stopping the leadering operation at a predetermined number of matrices from the end of the line there is associated the means for causing automatic transposition of the letters of the telephone number into numerals and, in the preferred embodiment of the invention which is described in this specification, the conventional counting pointer which is associated with the counting scale of the tape perforating machine is employed as the means for operating these means. Thus, in the operation of a tape perforating machine through the medium of auxiliary apparatus such as is disclosed in the aforesaid Letters Patent, the invention provides means for causing the movement of the counting pointer to a predetermined position on the counting scale to stop the operation of the leadering device of the perforating machine, and also to operate the means for causing letter to number transposition in perforating for the telephone number itself.

In the drawing forming part of this specification there are illustrated the conventional counting scale 2 and counting pointer 4 of a tape perforating machine such as the Teletypesetter, and reference is made to United States Letters Patent Nos. 1,968,056, 2,021,151, 2,083,608 and 2,189,545 for a more complete description of the structure and operation of this scale and pointer. The scale has a series of graduations extending from 0 at the right-hand end of the scale to 45 at the left-hand end, and the pointer moves from left to right over the scale. In operation, the TTS counting scale is set for the type size to be composed and for the measure of the line. As the various characters are touched by the operator's fingers on the keyboard of the auxiliary apparatus, the counting pointer 4 moves over the scale from left to right. However, when the spaceband lever is struck, the counting pointer remains stationary, but the counting scale, which is attached to the right-hand pointer 6, moves from right to left. Each movement of the scale represents the minimum width of the Linotype spaceband, while the left-hand pointer 8 moves a greater distance to the left, corresponding to the maximum thickness of the spaceband. Thus, the counting mechanism not only accumulates the sum of the brass widths of the matrices for a line, but it also indicates the total range of spread of the spacebands which will justify the line on the casting machine. In operation, when the counting pointer 4 is between the two justification pointers 6, 8 the line may be ended. The operator depresses the "return" and "elevate" keys of the keyboard of the auxiliary apparatus and proceeds with the next line.

The TTS keyboard comprises a plurality of keys representing all of the letters of the alphabet, the numbers 0 to 9, and various other character keys which are required for printing. This keyboard is well known and is illustrated in various United States Letters Patent, for example No. 2,000,029. In the drawing, a number of these keys are shown, these being the keys 10, 12, 14, which are the a, b and c keys, respectively, and key 16, which is the 2 key. In addition, the m, n and o keys of the TTS keyboard are shown but are not identified by reference numerals, but only by the letters of the alphabet which they represent. For purposes of simplicity not all of the letter keys of the TTS keyboard are shown in the drawing, but it will be understood that those not shown are included by reference, and the operation of the means provided by the invention for all of the keys will be made clear by description of the operation of the means provided in connection with the a, b, c and 2 keys.

There are also shown in the drawing the essential parts of the auxiliary apparatus provided by the inventions of my aforesaid Letters Patent and the Happel, Arvin and Murphy patent for operating the keys of the TTS. These parts of the auxiliary apparatus for operating the 2, a, b and c keys of the TTS keyboard comprise the 2, a, b and c keys of the keyboard of the auxiliary apparatus,

which keys are shown at 20, 22, 24 and 26, respectively, and which may be either the lower or upper case keys of the Linotype keyboard of the auxiliary apparatus. In accordance with the inventions described and claimed in said Letters Patent, depression of any one of the letter, number or other character keys of the keyboard of the auxiliary apparatus causes energization of a solenoid operatively associated with the corresponding letter, number or other character key of the TTS keyboard to operate the same and produce a characteristic tape perforation. The solenoids 28, 30, 32 and 34 are operatively associated, respectively, with the 2, a, b and c keys of the TTS and one terminal of the winding of each of these solenoids is connected to a source of electrical energy, while the armature of each solenoid is positioned above the associated key of the tape perforating machine keyboard.

The "2" key 20 of the auxiliary apparatus keyboard, when depressed, closes the contacts of a normally open switch 36, one contact of which is grounded at 38 and the second contact of which is connected to the second terminal of the winding of solenoid 28 by lead 40. Depression of key 20 closes switch 36 and completes the circuit through the winding of solenoid 28, energizing the same and causing the armature to depress the "2" key 16 of the tape perforating machine keyboard to produce the characteristic "2" tape perforation. All of the number keys of the keyboard of the auxiliary apparatus and of the tape perforating machine are constructed and operable and have associated with them the same parts as described in connection with the "2" keys 20 and 16 of the two keyboards. However, for purposes of simplicity of drawing and description only one other number key is illustrated in the drawing, this being the "6" key of both keyboards. Thus, the "6" key 50 of the keyboard of the auxiliary apparatus when depressed, closes a normally open switch 52, one contact of which is grounded and the second contact of which is connected to one terminal of the winding of a solenoid 54 through lead 56, the second terminal of the winding being connected to a source of electrical energy. Depression of key 50 closes switch 52 and completes the circuit through the winding of solenoid 54, energizing the same and causing the armature to depress the "6" key 58 of the tape perforating machine keyboard to produce the characteristic "6" tape perforation. As stated, the other number keys 1, 3, 4, 5, 7, 8, 9 and 0 of the auxiliary apparatus and the tape perforating machine are constructed, connected and operable and have the same parts as described in connection with the "2" and "6" keys of the two keyboards.

The "a" key 22 of the auxiliary apparatus keyboard, when depressed, closes a normally open switch 60, one contact of which is grounded at 38 and the second contact of which is connected to the movable contact 62 of a single-pole double-throw switch 64 which is normally in engagement with fixed contact 66 of the switch which, in turn, is connected to the open terminal of the winding of solenoid 30 by lead 68. Depression of key 22 will close switch 60 and complete the circuit through switch contacts 62, 66, lead 68 and the winding of solenoid 30, energizing the same and causing the solenoid armature to depress the "a" key 10 of the tape perforating machine keyboard to produce the characteristic "a" tape perforation. The "b" and "c" keys 24, 26 of the keyboard of the auxiliary apparatus are similarly connected to operate the "b" and "c" keys 12, 14 of the tape perforating machine. Thus, "b" key 24, when depressed, closes a normally open switch 70, one contact of which is grounded and the other contact of which is connected to the movable contact 72 of a single-pole double-throw switch 74, which is normally in engagement with fixed contact 76 of the switch which, in turn, is connected to the second terminal of the winding of solenoid 32 by lead 78. Depression of key 24 will close switch 70 and complete the circuit through switch contacts 72, 76, lead 78 and the

winding of solenoid 32, energizing the same and causing the solenoid armature to depress the "b" key 12 of the tape perforating machine to produce the characteristic "b" tape perforation. The "c" key 26, when depressed, closes a normally open switch 80, one contact of which is grounded and the other contact of which is connected to the movable contact 82 of a single-pole double-throw switch 84 which is normally in engagement with fixed contact 86 of the switch which, in turn, is connected to the open terminal of the winding of solenoid 34 by lead 88. Depression of key 26 will close switch 80 and complete the circuit through switch contacts 82, 86, lead 88 and the winding of solenoid 34, energizing the same and causing the solenoid armature to depress the "c" key 14 of the tape perforating machine to produce the characteristic "c" tape perforation.

The switch, solenoid and other means which have been described in connection with the a, b and c keys 22, 24, 26 of the auxiliary apparatus for operating the a, b and c keys 10, 12, 14 of the tape perforating machine are duplicated for all other alphabet letter keys of the two keyboards with the possible exception, if desired, of the "q" and "z" letter keys, which are not found on the usual and conventional telephone dials now in use. Because of this duplication it is not necessary to describe the means provided by the invention in connection with each alphabet letter key of the auxiliary apparatus keyboard for operating the corresponding letter key of the keyboard of the tape perforating machine. Further, for simplicity of disclosure, not all of the alphabet letter keys of the two keyboards are shown in the drawing, only the a, b, c, m, n and o keys being shown. However, all of the other keys of the two keyboards, with operative connections between them as described in connection with the a, b and c keys of the two keyboards, are incorporated herein by reference, and the disclosure is, and will be, so understood by those skilled in the art.

In accordance with the invention the alphabet letter keys of the keyboards of the auxiliary apparatus and of the tape perforating machine (in the present example the "q" and "z" keys are not included in this grouping) are divided into groups and each group is associated with one of the number keys of the tape perforating machine. In the example of the invention being described, which has to do particularly with setting type for a telephone directory, the telephone dial groupings are adopted and each group is associated with the number with which it is associated on the usual telephone dial. These groups and their associated numbers are set forth hereinbefore in this specification and need not be repeated here. However, reference to the list previously set forth will show that the a, b and c keys form a group which is associated with the number "2," and that the m, n and o keys form a group which is associated with the number "6."

In addition to the parts of the tape perforating machine and the auxiliary apparatus which are described above, the tape perforating machine has also an En (or Em) leader key 90 with which there is associated a solenoid 92 of the auxiliary apparatus, one terminal of which is connected by lead 94 to one fixed contact 96 of a single-pole double-throw switch 98 which is mounted on or adjacent to the counting scale 2 of the tape perforating machine, and which is normally in engagement with the movable contact 100 of the switch which, in turn, is connected to a source of electrical energy. The second terminal of the winding of solenoid 92 is connected to one contact of a normally open switch 102, the second contact of which is grounded at 38, the switch being normally open and being closed by depression of the En (or Em) leader key 104 of the auxiliary apparatus. In accordance with the inventions of my aforesaid Letters Patent, the En (or Em) leader key 90 of the tape perforating machine is operated by depression of the corresponding leader key 104 of the auxiliary apparatus, which closes switch 102 and completes a cir-

cuit through the winding of solenoid 92, energizing the same and causing the armature of the solenoid to depress the key 90.

This operation of the En leader key of the tape perforating machine causes a tape perforation to be produced which, in setting type, will produce either a short blank space or a short "leader," depending on whether or not there was a preceding "upper rail" or "lower rail" tape perforation. It will be understood that in perforating tape to be used in setting type for a listing in a telephone directory, the En space key 104 of the auxiliary apparatus will be operated successively to produce a line of short "leaders" extending from the end of the address (or from a following space) to the first numeral or letter of the telephone number itself. The number of key operations to produce leaders to fill this space will vary from line to line because of the differences from line to line in the number of key operations required to produce all of the tape perforations necessary to set the matrices for the name and address which form the first part of the listing. The number of leader key operations for each line is, therefore, unknown and the calculation thereof by the operator is time consuming and, therefore, costly.

Means are provided by the invention for stopping the operation of the leader key of the tape perforating machine at a predetermined number of type-unit spaces from the end of the line, thereby relieving the operator from the necessity of calculating the number of leader key operations he must make after completing the name and address listing (or after a space following the name and address listing) and, simultaneously with the stopping of the leader key, for causing the operation of any letter key, of any one of the groups of letter keys into which the letter keys of the two keyboards have been divided, to cause the operation of the number key associated with the group, thereby to produce the tape perforation characteristic of the number instead of the perforation characteristic of the letter.

The means provided by the invention for stopping operation of the leader key of the tape perforating machine comprise the fixed contact 96 and the movable contact 100 of the single-pole double-throw switch 98 which, as described, is mounted on or adjacent the counting scale 2 of the tape perforating machine. As hereinbefore stated, eight type matrices are required to set the conventional telephone number, which consists of two groups of three and four numerals, respectively, separated by a hyphen. As described hereinbefore, the counting pointer 4 of the tape perforating machine moves from left to right over the counting scale 2, descending the scale thereon and, when it reaches zero on the scale, indicating the end of the line. In accordance with the invention the switch 98 is so positioned with respect to the scale 2 that the movable contact 100 thereof is eight divisions up the scale from the zero indication, so that it is engaged by the pointer 4 when eight more matrices must be set in order to complete the line. When so engaged by the pointer the movable contact 100 is moved out of contact with the fixed contact 96 of the switch, thus disconnecting the winding of solenoid 92 from the source of power. As the leader key 90 can only be operated by operation of solenoid 92, because of the addition of the auxiliary apparatus to the tape perforating machine, the leader perforating mechanism of the tape perforating machine is rendered inoperative by disconnection of the solenoid winding from power.

The means provided by the invention for transposing the letters of a telephone number into numerals upon letter key operation comprise, first, the second fixed contact 110 of the single-pole double-throw switch 98. This fixed contact is normally out of engagement with the movable contact 100 of the switch, which normally engages fixed contact 96, but upon engagement of the movable contact by the counting pointer 4 (when the

pointer is eight units removed from the zero indication of the scale) the movable contact is moved into engagement with fixed contact 110 to thereby connect the fixed contact 110 to power through the movable contact. Fixed contact 110 is connected by lead 112 to one terminal of the winding of a relay 114, the other terminal of which is grounded at 38. The movable armature 116 of the relay is connected by link 118 to the movable contact of each of the two-pole double-throw switches which are included in the operating circuits connecting the letter keys of the tape perforating machine and the auxiliary apparatus. Thus, as shown in the drawings, the link is connected to the movable contacts 62, 72, 82 of the single-pole double-throw switches 64, 74, 84 which are associated with the a, b and c letter keys, and is also connected to the movable contacts of the single-pole double-throw switches associated with all of the other letter keys except only, if desired, the "q" and "z" keys. These movable contacts normally engage the fixed switch contacts which are connected to the windings of the solenoids which operate the letter keys of the tape perforating machine. Thus, the movable contacts 62, 72, 82 of the single-pole double-throw switches 64, 74, 84, which are associated with the a, b and c keys, normally engage the fixed switch contacts 66, 76, 86.

In accordance with the invention, each single-pole double-throw switch associated with a letter key is provided with a second fixed contact which is connected to the winding of the solenoid which operates the key of the tape perforating machine for the number which is associated with the group in which the letter key is included. Thus, each of the single-pole double-throw switches 64, 74, 84 is provided with a second fixed contact, these being shown at 120, 122, 124, respectively, and these fixed contacts are connected by leads 126, 128, 130, respectively, to the open terminal of the winding of the "2" key solenoid 28 through lead 40. Each of the three single-pole double-throw switches of each group of three letter key operators is so provided with a second fixed contact, which is connected to the winding of the solenoid which operates the key of the number which is associated with the group, which fixed contact is not normally engaged by the movable contact of the switch. Thus, as shown in the drawing, all of the second fixed contacts of the single-pole double-throw switches of the m, n, o group of letter key operating means are connected to the winding of solenoid 54 which operates the "6" key of the tape perforating machine, this being the number associated with the m, n, o group.

Operation

The operation of the means and apparatus provided by the invention will be described in connection with the perforation of tape for setting type to print the successive lines of a telephone directory, which is the example of uses of the invention being described in this specification.

Prior to operation of the tape perforating machine and the auxiliary apparatus, the single-pole double-throw switch 98 is set at a predetermined position along the counting scale 2 of the TTS so that the movable contact 100 thereof will be engaged by the counting pointer 4 when the pointer is removed from the zero indication on the scale by the number of matrix units equal to the number of matrices necessary to print the telephone number, which is eight for the telephone numbers now being used. The operator now operates the auxiliary apparatus of the tape perforating machine to perforate tape to set type for the name and address of the listing, after which it is usual to perforate the tape to set a spaceband. The En (or Em or both) leader key of the auxiliary apparatus is now operated for an indefinite number of times, which number need not be known to the operator, until the counting pointer 4 engages the movable contact 100 of the single-pole double-throw switch 98, moving the same out of engagement with fixed contact 96 and into engage-

ment with fixed contact 110. This disconnects fixed contact 98 from the source of power and de-energizes solenoid 92, thus stopping the operation of the leader key 90 of the tape perforating machine and preventing further operation until the counting pointer 4 moves to the left on scale 2 and out of engagement with movable contact 100, which takes place upon depression of the "return" key when the line is completed.

The engagement of movable contact 100 with fixed contact 110 connects the fixed contact to power and energizes relay 114, causing the armature thereof to move to the left as shown in the drawing. This moves link 118 in the same direction, causing all of the movable contacts of the single-pole double-throw switches which form part of the operating circuits connecting the letter keys of the auxiliary apparatus to those of the tape perforating machine, such as movable contacts 62, 72, 82, which are associated with the a, b and c keys, to move out of engagement with the fixed contacts which are connected to the solenoids which operate the letter keys of the tape perforating machine, such as fixed contacts 66, 76, 86, and into engagement with the fixed contacts which are connected to the solenoid which operates the key of the tape perforating machine for the number which is associated with the letter group, such as the fixed contacts 120, 122, 124. When this takes place the letter keys of the tape perforating machine are rendered inoperative, as they may only be operated by the solenoids of the auxiliary apparatus, and depression of any letter key of the auxiliary apparatus energizes the operating solenoid for the number associated with the group in which the depressed letter key is included. Thus, after engagement of switch contact 100 and 110, depression of any one of the a, b, c letter keys of the auxiliary apparatus will cause depression of the "2" key of the tape perforating machine. Depression of any one of the m, n, o letter keys of the auxiliary apparatus will cause depression of the "6" key of the tape perforating machine, and so on for all of the grouped letters.

While I have described and illustrated one form which my invention may take, it will be apparent to those skilled in the arts to which it relates that other embodiments, as well as modifications of that disclosed, may be made and practiced without departing in any way from the spirit or scope of the invention, for the limits of which reference must be made to the appended claims.

What is claimed is:

1. An auxiliary apparatus for operating the keys of the keyboard of a tape perforating machine having a plurality of letter keys and a plurality of number keys each producing, when depressed, a tape perforation characteristic of the letter or number of the key, said apparatus comprising a keyboard having keys corresponding, respectively, to the letter and number keys of the machine keyboard, first means operable upon depression of any letter or number key of the auxiliary apparatus to operate the corresponding letter or number key of the machine keyboard to produce a tape perforation characteristic of the letter or number of the depressed key of the auxiliary apparatus, the letter keys of the auxiliary apparatus being divided into a plurality of groups each of which corresponds to one of the number keys of the machine, and means operable to cause depression of any letter key of any one of said groups to operate the machine number key corresponding to the group in which the depressed letter key is included.

2. An auxiliary apparatus for operating the keys of the keyboard of a tape perforating machine having a plurality of letter keys and a plurality of number keys and a leader key, each producing when depressed a tape perforation characteristic of the letter, number or leader of the key, and having also a counting scale having divisions each representing the width of the type to be used and a counting pointer movable over the scale to indicate the accumulated width of set type, said auxiliary

apparatus comprising a keyboard having a leader key and electrical means operable upon depression thereof to operate the leader key of the machine, a normally closed switch associated with the counting scale of the tape perforating machine and positioned to be engaged and opened by the counting pointer at a predetermined position on the scale, and means operable upon opening of said switch to de-energize the electrical means for operating the leader key of the machine upon depression of the leader key of the auxiliary apparatus.

3. An auxiliary apparatus for operating the keys of the keyboard of a tape perforating machine having a plurality of letter keys and a plurality of number keys and a leader key, each producing when depressed a tape perforation characteristic of the letter, number or leader of the key, and having also a counting scale having divisions each representing the width of the type to be used and a counting pointer movable over the scale to indicate the accumulated width of set type, said auxiliary apparatus comprising a keyboard having keys corresponding, respectively, to the letter, number and leader keys of the machine keyboard, electrical means operable upon depression of any letter or number key or the leader key of the auxiliary apparatus to operate the corresponding letter, number or leader key of the machine keyboard to produce a tape perforation characteristic of the letter, number or leader of the depressed key of the auxiliary apparatus, the letter keys of the auxiliary apparatus being divided into a plurality of groups each of which corresponds to one of the number keys of the machine, means associated with the counting scale of the tape perforating machine and positioned to be engaged by the counting pointer at a predetermined position on the scale, means operable upon engagement of said means by the counting pointer to prevent tape perforation upon depression of the leader key of the auxiliary apparatus, and means also operable upon engagement by the counting pointer to cause depression of any letter key of any of said groups to operate the machine number key corresponding to the group in which the depressed key is included.

4. An auxiliary apparatus for operating the keys of the keyboard of a tape perforating machine having a plurality of letter keys and a plurality of number keys and a leader key each producing when depressed a tape perforation characteristic of the letter, number or leader of the key, and having also a counting scale having divisions each representing the width of the type to be used and a counting pointer movable over the scale to indicate the accumulated width of set type, said auxiliary apparatus comprising a keyboard having keys corresponding, respectively, to the letter, number and leader keys of the machine keyboard, electrical means operable upon depression of any letter or number key or the leader key of the auxiliary apparatus to operate the corresponding letter, number or leader key of the machine keyboard to produce a tape perforation characteristic of the letter, number or leader of the depressed key of the auxiliary apparatus, the letter keys of the auxiliary apparatus being divided into a plurality of groups each of which corresponds to one of the number keys of the machine, a switch associated with the counting scale of the tape perforating machine and positioned to be engaged by the counting pointer at a predetermined position on the scale, means operable upon engagement of said switch by the counting pointer to de-energize the electrical means for operating the leader key of the machine upon depression of the leader key of the auxiliary apparatus to prevent tape perforation upon depression of the leader key of the auxiliary apparatus, and means also operable upon engagement by the counting pointer to cause depression of any letter key of any of said groups to operate the machine number key corresponding to the group in which the depressed key is included.
